COMBINATION OPTICAL OBJECTIVE AND MOTOR HOUSING

Paul Himmelsbach, Kreuznach, Rhineland, Germany, assignor to Jos. Schneider & Co., Optische Werke, Kreuznach, Rhineland, Germany, a corporation of Germany

Filed Mar. 29, 1961, Ser. No. 64,535

Term of patent 14 years

Claims priority, application Germany Feb. 4, 1961

(Cl. D57—1)

FIG. 1

FIG. 2

FIG. 3

FIG. 4

FIG. 1 is a perspective view of one side of a combination optical objective and motor housing, showing my new design;

FIG. 2 is a perspective view of the opposite side thereof;

FIG. 3 is a top view thereof; and

FIG. 4 is a bottom view thereof.

I claim:

The ornamental design for a combination optical objective and motor housing, as shown.
